CLAIM

The ornamental design for a floral wrapping material, as shown and described.

DESCRIPTION

FIG. 1 is a front elevation view of a floral wrapping material showing our new design;

FIG. 2 is a rear elevation view thereof;

FIG. 3 is an end elevation view thereof, the opposite end being identical;

FIG. 4 is a top plan view thereof; and;

FIG. 5 is a bottom plan view thereof.

The drawing is shaded and lined to show contrasting colors.
